UNITED STATES PATENT OFFICE.

HARRY A. S. READ, OF LAWRENCE, MASSACHUSETTS, ASSIGNOR TO PLYMOUTH MILLS,
OF NEW YORK, N. Y., A CORPORATION OF NEW YORK.

DESIGN FOR A RUG.

47,616.

Specification for Design.

Patented July 20, 1915.

Application filed May 28, 1915. Serial No. 31,065. Term of patent 3½ years.

To all whom it may concern:

Be it known that I, HARRY A. S. READ, a citizen of the United States, residing at Lawrence, in the county of Essex and State of Massachusetts, have invented a new, original, and ornamental Design for a Rug, of which the following is a specification, reference being had to the accompanying drawing, forming part thereof.

The figure is a top plan view of a portion of a rug, showing my new design.

I claim:—

The ornamental design for a rug, as shown.

HARRY A. S. READ.
